(57) **CLAIM**

We claim the ornamental design for a cooking apparatus unit, substantially as shown and described.

DESCRIPTION

FIG. 1 is a front perspective view of an embodiment of a cooking apparatus unit showing our new design;

FIG. 2 is a front elevational view thereof;

FIG. 3 is rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dotted line showings in the drawings are for the purpose of illustrating environmental structure and form no part of the claimed design.
